ABSTRACT: A collapsible shipping container having its vertical walls provided with tongues and notches to interfit, and corner locking members to hold the sides together. The base fits within the setup sides. Each side has a unitary leg which includes a base support. Locking means are provided to hold the base in position, and an alternative design prevents shearing between the base support and the leg, should the loaded box be dropped on a corner.

COLLAPSIBLE SHIPPING CONTAINERS

This invention relates to reusable shipping containers which can be collapsed and returned to the factory in knocked-down condition, and is particularly designed for the protection and shipment of machinery, e.g. of engines and compressors, etc.

It is a considerable advantage to enclose machinery during freight shipment completely. Many purchasers require that the machines be shipped to them in containers where they will be protected against weather, damage and spills from other items in the freight, and especially that the machines be protected from pilferage of parts.

However, full crating is expensive. Its demand for lumber is high. Particularly in marine shipments, where the charge for freight is calculated on a volume rather than a weight basis, returning the setup but empty machinery container can cost more than the value of the crate. The advantage of a container which can be returned knocked down and occupy merely the volume of flat lumber is obvious.

The container which will be described is designed to hold reasonably heavy pieces of equipment, but the same design holds considerable advantage for the shipping of miscellaneous goods which may be packed in the containers and sealed against pilferage.

The container can be understood from the following specification, and from the drawings in which

FIG. 1 is a perspective view of the container with breakaways in section.

FIG. 2 is a partial view of the corner posts showing end stops.

FIG. 3 is a partial side view of the container showing the dropped base and the support blocks.

FIG. 4 is a partial perspective view of a modified corner and channel support.

As shown in FIG. 1, the collapsible container, 10, is built up from four sidepieces, 11, the vertical margins, 12, of which are formed into tongues 13, and cooperating notches, 14. A slot, 15, which extends from top to bottom of the side is cut on the outer vertical face of each side, 11, adjacent the margins, 12. The bottom margin is cut back as at 16, to provide clearance for the forks of a lift truck.

Legs, 17, for the container are formed not only by that portion, 20, of the side, 11, which extends between the lower outer corner and the cut out portion, 16, but also by a block, 18, fastened to the leg portion of the side, 11, in any appropriate manner. Each leg is covered or protected with a metallic sheathing, 19, which may, e.g. be held in proper assembled relationship by mechanical fasteners or by rivets, 21.

The blocks, 18, support the base, 22, which, if the container is to be used for the shipment of heavy machine parts, may have the extra support of rails, 23, or stiffeners affixed to the base.

The base is locked in position and prevented from rising by base retaining blocks, 24, which are fastened on the inner face of the sides, 11, in such a position that the base, 22, and rail, 23 (if one is used) is retained between the upper face, 25, of the base support blocks, and the lower face, 26, of the base retaining blocks, 24.

If light loads only are to be shipped, the vertical position of the floor in relation to the height of the cutout, 16, is not important, but if any substantial weight is to be put in the container, it is highly advantageous to place the base, 22, at such a height that the bottom surface, 27, of base, 22, lies below the crest, 28, of the fork-clearing cutout, 16. When so arranged, the forks of a lift truck support and lift the entire base, they cannot engage perhaps only one vertical side and so wrench the container.

The container is assembled by interfitting the sides, 11, at right angles, fitting the tongues, 13, into the notches, 14. The sides, 11, are locked in position by the corner posts. Each post, 29, comprises a right angle section having marginal flanges, 31, bent at right angles to the arms, 32-33. Each flange 31, is preferably continuous along the outer margins of the posts. On one end of the post, 29, either one or both of the

arms, 32, is bent inwardly at an angle to form a stop, 33 (see FIG. 2).

By pushing the corner posts, 29, downwardly with the marginal flanges, 31, in engagement with the slots, 15, the container is locked together. Three sides are first locked together, then the base, 22, is slid in between the base supports, 18, and the base retainers, 24. The posts, 29, cannot fall downwardly because the stop, 33, engages the top margin of a side, 11.

Drop tests have shown that if the load is heavy and the container lands on the outer corner of a leg, the base support block, 18, may shear off at or near the joint between the block, 18, and the leg portion, 20, of the side 11. However, if the leg portion, 20, be shortened so that the base support block, 18, rather than the extended leg portion, 20, receives the corner blow, the base, 22, and whatever it carries remain supported. Shearing as a result of a corner blow does not take place, and usually in ordinary mishaps, but slight damage results.

FIG. 4 illustrates this improvement. The base support blocks, 18a, extend below the lower margin, 34, of the sides, 11-11. The metal sheathing, 19a, then is bent so that its lower surface includes a step, 35, one part, 36, of which covers the lower margin, 34, of a side, 11, and the remaining portion, 37, forms a protection and skid shoe for the base support block, 18a.

FIG. 4 also shows a sheathing for the lower edge of a side, 11, adapted also to receive and to support the base, 22. This sheathing, 38, (conveniently an extruded shape) includes two channel sections, 39 and 41. Channel, 39, is directed upwardly and houses the lower cutout edge of a side 11, and channel, 41, is directed horizontally inwards and receives the container base, 22. Damage to the walls, 11, from the forks of a lift truck is reduced because of the metallic sheathing.

The container is closed by a top, 42, which preferably overlaps the setup sides, 11, by a small amount—say one eighth of an inch—and forms a drip cornice. Weatherproofing is aided by placing a compressible gasket, 43, between the sides, 11, and the top. The gasket is usually adhered to the top.

Sealing is accomplished by box strapping, 44, which, in order to insure its correct placement, is fitted into the shallow notches, 45. Blocks, 46—which can also be full marginal rails—are fastened to the inside of the top, 42, directly behind each notch, 45, leaving just enough clearance for the thickness of a side. When the top is in place, the pull of the box strapping, 44, is resisted by the blocks, 46, and the top 42, in compression. The sides, 11, cannot bow inwards as the strapping is pulled taut.

To unpack and disassemble the container, the strapping, 44, is cut, the cover is lifted off, two of the corner posts, 29, are withdrawn, and one side is removed. The three-sided box usually remains stable while the machine is being unbolted from the base or from the base and the stiffening supports.

To collapse the container completely, the two remaining corner posts, 29, are removed. Nothing remains but six substantially flat parts and the metal corner posts which can be strapped together and returned to the shipper with significant saving in return freight and stowage space.

I claim:

1. A collapsible shipping container having
  - a. sidewalls provided with tongues and notches adapted to interfit with the tongues and notches of an adjacent side,
  - b. slots formed in the outer face of each side extending transverse of the side adjacent each end,
  - c. corner locking members having end stops to position said members and inturned marginal flanges adapted to fit into the said transverse slots and lock the interfitted sides together,
  - d. each of said sides having a cutback to provide clearance for a fork lift and a leg area adjacent the cutback portion,
  - e. a base support block backing the leg area of each of said sides,
  - f. a bottom adapted to fit within the setup sides of said box and to rest on the side support blocks,

- g. a top having means to resist the inward bowing of each side when pulled inward by a box strapping, and
- h. each of said legs bearing metal sheathing which form a skid-shoe for said legs.

2. A collapsible shipping container having

- a. sidewalls provided with tongues and notches adapted to interfit with the tongues and notches of an adjacent side,
- b. slots formed in the outer face of each side extending transverse of the side adjacent each end,
- c. corner locking members having end stops to position said members and inturned marginal flanges adapted to fit into the said transverse slots and lock the interfitted sides together,
- d. each of said sides having a cutback to provide clearance for a fork lift, and a leg area adjacent the cutback portion,
- e. a base support block backing the leg area of each of said sides,
- f. a bottom adapted to fit within the setup sides of said box and to rest on the side support blocks,
- g. a top having means to resist the inward bowing of each side when pulled inward by a box strapping,
- h. each of said legs bearing metal sheathing which forms a skid-shoe for said legs, bearing
- i. the said support base blocks extending downwardly below the extent of the leg portion of said sides whereby the force of a blow on a bottom corner of said container will be transmitted directly by said base support to the base and its load, and shearing between the base support and side is minimized.

3. A collapsible shipping container having

- a. sidewalls provided with tongues and notches adapted to interfit with the tongues and notches of an adjacent side,
- b. slots formed in the outer face of each side extending transverse of the side adjacent each end,
- c. corner locking members having end stops to position said members and inturned marginal flanges adapted to fit

into the said transverse slots and lock the interfitted sides together,

- d. each of said sides having a cutback to provide clearance for a fork lift, and a leg area adjacent the cutback portion,
- e. a base-support block backing the leg area of each of said sides, and

f. a dual channel member provided with vertical and horizontal channels, the said vertical channel enclosing the lower cutout margin of each side, and the said horizontal channel being fitted over a margin of the base.

4. A collapsible shipping container having

- a. sidewalls provided with tongues and notches adapted to interfit with the tongues and notches of an adjacent side,
- b. slots formed in the outer face of each side extending transverse of the side adjacent each end,
- c. corner locking members having end stops to position side members and inturned marginal flanges adapted to fit into the said transverse slots and lock the interfitted sides together,
- d. each of said sides having a cutback to provide clearance for a fork lift, and a leg area adjacent the cutback portion,
- e. a base support block backing the leg area of each of said sides,
- f. a bottom adapted to fit within the setup sides of said box and to rest on the side support blocks,
- g. a top having means to resist the inward bowing of each side when pulled inward by a box strapping,
- h. each of said legs bearing metal sheathing which forms a skid-shoe for said legs, and
- i. wherein the base-supporting blocks are positioned to maintain the bottom surface of said base in a horizontal plane slightly below the cutout margins of said sides, whereby the forks of a lift truck will engage transversely the entire width of the bottom panel and so relieve the sides of the said containers from the lifting burden.
